(No Model.)

W. BEALE.

HOUSEHOLD FURNITURE.

No. 339,614.

Patented Apr. 13, 1886.

UNITED STATES PATENT OFFICE.

WEISEL BEALE, OF NEW MADRID, MISSOURI.

HOUSEHOLD FURNITURE.

SPECIFICATION forming part of Letters Patent No. 339,614, dated April 13, 1886.

Application filed November 23, 1885. Serial No. 183,760. (No model.)

To all whom it may concern:

Be it known that I, WEISEL BEALE, a citizen of the United States, residing at New Madrid, in the county of New Madrid, State of Missouri, have invented certain new and useful Improvements in Household Furniture, of which the following is a specification, reference being had therein to the accompanying drawings.

10 My invention relates to an improved device which is applicable to drawers for furniture; and it consists in an angular bracket or bearing provided with means for preventing a drawer from binding, as will be fully understood from 15 the following description, when taken in connection with the annexed drawings.

Figure 1 is a sectional view taken vertically and longitudinally through a bureau, showing my invention applied to three drawers, one of 20 which is partly drawn out. Fig. 2 is a perspective view of my improved angular bracket or bearing provided with anti-friction rollers. Fig. 3 is a cross-sectional view of a bearing-rail having a double inverted-V-shaped 25 surface adapted for a concave anti-friction base-roller or for a Δ -shaped slide. Fig. 4 is a perspective view showing my improved angular bracket or bearing without anti-friction rollers.

30 A designates, for example, a bureau provided with drawers D D D and horizontal strips or bearers B B B, which bearers have inverted-V-shaped upper rolling surfaces, b, and flat or horizontal bottom surfaces, a, as 35 clearly indicated in Fig. 3. These bearers or horizontal rails serve a twofold purpose, as will hereinafter appear, and they are secured to the back of the bureau and to the facing-strip C, as shown in Fig. 1.

40 It is obvious that my invention is applicable to a single drawer of a piece of furniture. I will especially refer to one drawer D and the case or recess therefor.

E designates my improved angular bracket 45 or bearing, which is made of suitable material and perforated to receive screws, by means of which it is rigidly secured to the rear or inner end of the drawer and at the middle of the width thereof. This device consists of a vertical portion, c, preferably terminated at both 50 ends by a right angular lip, d, as shown in Fig.

2, whereby the bracket or bearing is reversible, the lowest lip being secured to the bottom of the drawer and the upper lip overhanging the drawer-space. In this Fig. 2 I have represented the upper angle notched out at f to receive a cylindrical roller, h, and at the lower angle I show a notched-out recess, g, in which I apply a concave roller, i. I have thus shown how I am able to prevent lateral 55 displacement or binding of a drawer, and at the same time to afford rear rolling bearings therefor. It is obvious that the cylindrical roller bears upward against the flat surface a of the upper rail B, and that the concave roller i bears upon the double inclined surfaces b of the lower rail B; and it is also obvious that the bracket E affords a substantial brace for the drawer to sustain it when heavily loaded between its two rails and drawn partly out of 60 its chamber. The rollers i are frustra of cones. The bearing-surfaces are especially adapted to impinge against the flat sides of an inverted-V-shaped rail.

My improved bracket, constructed as above 75 described, may be provided with a right cylindrical roller at its upper end, seated in the notch of the upper angle, and adapted to bear against a bar B, the lower roller having a notch in it.

80 It is clearly obvious that the gist of my invention consists in a bracket or flanged piece having a horizontal guide on its upper end adapted to serve as an upward right angular bearer, and a V-shaped groove or bearer on 85 its lower end adapted to prevent lateral displacement of the drawer, and also to prevent binding of the same. It is also obvious that this bracket is reversible—that is to say, it can be turned end for end, and the bars B 90 adapted for its different positions.

I am aware that circularly-concave rolls have been used before my invention to prevent lateral displacement or binding of a drawer in drawing it out or pushing it in. I broadly 95 disclaim such devices.

Having described my invention, what I claim, and desire to secure by Letters Patent, is—

1. A bracket for drawers, provided with an- 100 gular extensions, a flat bearing, and a V-shaped bearing adapted for application to the rear or

inner end of a drawer and for rails B, substantially as described.

2. The combination, with a drawer-bracket, of a cylindrical roller and a concave roller, substantially as described.

3. A bracket adapted for the rear end of a drawer, having right angular extensions and recesses at the angles thereof, in combination with anti-friction rollers applied in said recesses, substantially as described.

4. A drawer-bracket consisting of a vertical perforated portion, a right angular perforated portion, a recess in the angle, and an anti-friction roller therein, as specified.

In testimony whereof I affix my signature 15 in presence of two witnesses.

WEISEL BEALE.

Witnesses:

A. G. MATHEWSON,
R. PHELON.
